PROJECTILE

Hubert Wellcome, Bayside, N. Y.

Application April 5, 1939, Serial No. 266,067

20 Claims. (Cl. 102—63)

The present invention relates to ordnance projectiles of the bolas type designed primarily for use against aircraft but adaptable for other uses.

The invention has for an object to provide an improved projectile of the type wherein a bolas is projected in compact condition and spread as it approaches the target.

Another object is to provide a projectile comprising a bolas consisting of weights connected by wires which wires are so coiled that they can readily uncoil in flight.

Another object is to provide a bolas, the wires of which will have a low resistance to flight through the air.

Another object is to make provision whereby rotation of the weights will not unduly twist the wires.

Another object is to make provision for increasing the rotation of the weights of the bolas about the centre of the projectile thereby increasing the energy available for spreading the bolas.

The present invention provides a projectile wherein a bolas is adapted to be released from an enclosing shell and spread with considerable energy to extend over a wide area. The bolas weights are spread by centrifugal force and under conditions such that they move outward radially with substantially equal angles between their trajectories thereby providing a desirable even spread. Provision is made for increasing the rate of rotation of the group of weights over the rate of rotation of the shell for the purpose of increasing the energy available for spreading the bolas at the moment of release from the shell. Suitable swivel connections between the wires and weights permit the rotation of the weights without causing an undesirable twisting of the wires. The connection is designed with due regard to the rotative movement of the weight which is derived from the rotation of the shell in flight.

In the illustrated embodiment the wires of the bolas are twisted together in the form of a cable which is coiled within the shell. The arrangement of the coil is such that the cable is drawn from the centre of the coil by the weights as they are projected radially outward by centrifugal force. By this arrangement the rotative inertia of the coil does not act against the pull of the weights. The twist of the cable is so designed that as the weights pull there will not be too great a difference between the twisting in one direction due to some factors and the twisting in the other direction due to other factors.

The nature and objects of the invention will be better understood from a description of an illus-

trative embodiment thereof for the purpose of which description reference should be had to the accompanying drawings forming a part hereof and in which—

5 Figure 1 is a central longitudinal sectional view of a projectile embodying certain principles of the invention,

Figs. 2A and 2B are horizontal sectional views taken on the line Y—Y' of Fig. 1 showing the 10 positions of the clip supporting bracket 8H respectively in position before and after the first two layers of the coil of wire have been drawn from within the coil,

Fig. 3 is a horizontal sectional view taken on 15 the line X—X' of Fig. 1,

Figs. 4A and 4B are views showing a modified 20 form of connection between the weight and bolas wire,

Fig. 4C is a bottom view of the weight shown 25 in Fig. 4A,

Fig. 4D is a sectional view taken on the line Z—Z' of Fig. 4C,

Fig. 5A is a plan view of the weight supporting 30 segments 12B,

Fig. 5B is a vertical sectional view of the cover 35 plate 12 and supporting segments 12B,

Fig. 6A is a plan view of the clip supporting bracket 8H,

Fig. 6B is a central sectional view of the spacing 40 ring 16,

Fig. 6C is a view in elevation of one of the clip 45 supporting brackets 8H,

Figs. 7A and 7B are respectively a bottom plan 50 and a sectional view of the outer member 17A of the wire clip,

Fig. 7C is a sectional view of the intermediate 55 member 17C of the clip 17,

Fig. 8A is a vertical sectional view of another 60 form of wire clip shown as applied for securing together round wires,

Fig. 8B is a sectional view taken on a line between the members 10A and 10B of the clip shown 65 in Fig. 8A,

Figs. 9A and 9B are sectional views showing 70 respectively seven and six streamlined wires twisted together,

Fig. 10 is a view of a modified form of connection between the weight and wire,

Figs. 11 and 12 are respectively plan and 75 sectional views showing a modified form of weight and connection thereto, and

Fig. 13 is a diagrammatic view of the projectile 80 in flight after ejection of the bolas from the shell and at a moment when the bolas is partly 85 but not entirely spread.

In the illustrative embodiment of the invention shown in Fig. 1 the shell 1 with a shell base 2 and a shell head 3 carries a bolas and a charge of explosive 4 positioned, upon explosion, to project the bolas from the shell. The usual nose cap and timing fuse are not shown in the drawings but will be fitted into the shell head 3 as is usual practice. The threaded connection 2A between the base and body of the shell may be welded, if desired, for greater strength. The threads 3A of the head are designed to shear upon explosion of the charge 4. A rotating band 6 is provided as usual and it will be assumed that it gives a right handed rotation to the shell. The bolas comprises wires 7 twisted together and coiled within the casing 8 and weights 9 suitably connected to the ends of the wires.

It is to be noted that the chamber within the shell is tapered forwardly to receive the casing and the coil of bolas wires and the inner casing preferably is tapered to conform to the shape of the interior of the shell. This taper facilitates the projection of the bolas from the shell upon ignition of the explosive charge.

The weights are centrally bored and the ends of the wires 7 are rotatably secured therein. As shown, the ends of the wire are formed into loops 1B held by ferrules 9N and secured in cast members 9K rotatable in the bolas. Roller bearings 9J provide free rotation of the weights relative to the wires. The wires are protected and reinforced by copper tubes 9F to prevent too sharp bending and fracture of the wires close to the weights. The bores in the weights are closed by heavy metal plugs 9S threaded into the bores and provided with turning sockets 9T.

An igniting tube 11 is held in central position at the head end of the shell by a plate 8D. It is connected to the base of the shell by a coupling 11A having ignition transfer apertures 11B covered by wax paper 11C as is usual practice.

The weights must be supported to withstand the force of the explosion. As shown, a pressure plate 12 closes the explosive chamber and between this and the weights separate segmental plates 12B are provided, as indicated in Figs. 1, 5A and 5B. Each of these plates is formed with a slot to receive the wire and the reenforcing tube 9F looped downwardly therein from the weight above. The plate 12 and the segments 12B may be formed with rotating tongues 12A. The weights also are provided with similar rotating tongues 9E, all of which rotating tongues engage corresponding lands on the interior of the shell and serve to give an additional rotation to the weights as a group when they are projected from the shell upon ignition of the explosive charge.

The several wires are connected at the centre of the bolas by a suitable wire clip 17. The clip is held in position on the igniting tube 11 and is supported on a plurality of Z-shaped brackets 8H (Figs. 1, 6A and 6C) each of which is supported on a shoulder 8K in the shell and is held inward by a projection 8I which bears against the coil of wire to prevent radial outward movement until the wire is uncoiled. After the first two layers of the coil of wire are drawn out the Z-shaped brackets spread by centrifugal force from the position shown in Figs. 1 and 2A to the position shown in Fig. 2B and release the clip 17.

Between the upper horizontal flanges of the brackets and the coil of bolas wire a copper spacer 15 is provided to securely hold the wire in place. Upstanding lugs 15B inhibit rotation. The wire may be soldered to the copper.

The clip 17 comprises a central member 17B threaded at the top to receive the nut 17F. A sleeve 17C shown in Fig. 7C, provided with grooves in which the ends of the streamlined wires 7 are received and securely soldered, fits on the tapered portion of the central member 17B and is surrounded by an outer sleeve 17A (Figs. 7A and 7B) which in turn is held in place by the nut 17F. Lugs 17K engageable with the brackets 8H inhibit rotation. The narrow edges of the streamlined wires face inward so that in flight the wide portion will be forward in the best flight position near the clip. The shape of the wire and its stiffness will tend to maintain at least a large portion of the wire in the best position for minimum air resistance. At a point near the clip 17 and also at a point near the weights, in other words at the ends of the coil, the wires 7 are held together by rings 17F of frangible material which will readily break when substantially stressed.

In Figs. 8A and 8B is shown another form of connection between the wire 7 and the weight. As herein shown, the weight comprises a metal shell 9P filled with cast metal 9G and including a pin 9M which passes through an eye formed in the wire. A ferrule 9N clamps the end of the wire to form the eye. The wire has a measure of angular movement in the slot 9R provided for this purpose. As the weight leaves the shell, its rotation may cause the wire to wind to some extent on the weight, but the drag of the wire will ultimately stop such rotation and again unwind the wire. The connection is made at the side of the weight to have this action.

In Figs. 8A and 8B is shown another form of clip comprising a central rivet member 10C which holds together the upper and lower members 10A and 10B complementarily grooved to receive the wires 7H. In Fig. 8B the clip is shown as mounted on the igniting tube 11.

When the bolas is projected from the rapidly rotating shell the weights will move radially outwardly thus pulling the wire from within the coil to spread the bolas. The movement of the weights and wires relative to the coil as all continue their forward movement after discharge from the shell 1 will be more or less as indicated diagrammatically in Fig. 13. The coiling of the wire and the twist of the cable is so arranged that as the bolas is spread as the result of the centrifugal force, the wires will be drawn from within the coil without tangling and without such excessive twist as might interfere with the spreading of the weights.

When the weights are free from the shell, they would all move in substantially straight lines tangent to the circle in which they move at the moment of release if there were no resistance due to pull of the wires. On the other hand if the wires entirely resisted movement outwardly the weights would move in a circle of the diameter permitted by the effective length of the wires. Having this in mind, it will be clear that under some conditions of paying out of the wires, the bolas would be a rapidly rotating unit. In some circumstances the wires could pay out relatively slowly while the weights moved in rotation about the centre constantly pulling on the wires. As the wires pay out, furthermore, the rate of rotation of the unit as a whole would decrease substantially in proportion to the increase of radius.

It is important that the arrangement should be such that the wires will not twist too much on themselves and thereby prevent the outward movements of the weights.

The several factors contributing to the twist

EXPLOSIVE DEVICES

38

2,373,363

3

of the cable of wires after it uncoils from within the coil can be correlated to produce the necessary conditions.

Three principal factors contribute to the twist of the cable. The first is the rotation of the coil as a unit relative to the group of weights. The number of twists which will be given to the cable as the result of this relative rotation will depend upon the speed of rotation and the duration of the time of uncoiling of the cable. The second factor is the twist or wrap of the cable due to the uncoiling of the cable merely. This will be one twist for each turn of the coil. The third factor is the twist of the cable as coiled.

Two principal factors will contribute to the pulling of the cable from the coil, the pull of the weights due to centrifugal force and the pull on the wires in a direction opposite to the direction of flight due to the resistance of the air to the movement of the wires. The pull due to resistance of the air will be considerable after a substantial length of the wire is paid out and may tend to provide a substantial length of wire pulled out in twisted condition immediately behind the coil.

The rate of rotation of the coil as a unit during the uncoiling of the cable will not necessarily be the same as the rotation of the weights as a group even at the moment of ejection of the bolas from the shell.

The explosion of the charge 4 will eject the bolas but at the same time it will cause a rotation of the group of weights as the helical rotating projections 9E engage the corresponding lands provided in the shell walls. The coil rests on the weights with a hard solder, copper or equivalent ring 7E forming a connection between the weights and the coiled wire. If the connection between the ring 7E and the weights is a more or less keyed connection, and if the casing 8 is also substantially keyed to the weights, as it may be by its flange 8A, then the coil may be given the same rotation as the group of weights. On the other hand if the connection between the ring 7E and the weights is a substantially anti-frictional connection, the coil may receive relatively little of the additional rotation given to the weights. Either arrangement is feasible since the relative rotation between the weights and coil during the ejection of the bolas from the shell is not so great but that the relative twist can be provided for.

The rate of rotation of the weights about the axis of flight will determine the centrifugal force with which the weights are projected outwardly when freed from the shell and ordinarily it is desirable to increase the rotation above that of the rotation of the shell, in order to increase the force of projection of the weights which is available to draw out the wires from the coil. The same consideration, however, does not attach to the coil and the most advantageous rate of rotation of the coil is not necessarily the same as the most advantageous rate of rotation of the weights.

The number of twists given to the cable during the period of uncoiling of the cable from within the coil may be calculated or estimated with sufficient accuracy. We will assume that this will be a right hand twist. The number of twists given to the cable by the uncoiling will be equal to the number of turns of the coil, and in the arrangement shown this will be left handed. If the cable as coiled is given a twist on itself, corresponding to the difference and in the direction

to supplement the lesser of the two twists above, then the twist of the cable will not interfere with the spreading of the weights due to centrifugal force. The twist given to the wires in the coil is well below the elastic limit so that no set is given to the wire. Accordingly, when the wire is entirely uncoiled, if there is any residual twist of the cable due to lack of perfect compensation of the influencing factors, the wires will readily untwist to permit the weights to move outward to the maximum possible distance. If desired, the twist given to the cable during coiling may be different in different parts of the coil the better to meet the conditions of uncoiling and untwisting.

It is to be noted that the untwisting of the cable untwists each wire with obvious advantages.

Under usual conditions it is preferable that the coil should be wound in the direction such that the wire will rotate toward the point of pull off, thus facilitating rather than retarding the pull off. In this arrangement the twist given to the cable by the rotation of the coil is opposite the twist given by pull off, so that they tend to counteract each other. As a variation of the arrangement shown, the coil casing may be so split that it will fall away when ejected from the shell and the wires may be so coiled as to pull from the outside of the coil instead of from the inside. In that case the direction of rotation of the coil should be such as to pay off the cable of coils leading to the weights. This arrangement has some obvious advantages including low resistance to the pull of the weights. The direction and extent of twist of the wires should be designed with due consideration to the rotation of the coil and manner of uncoiling of the wires.

In Fig. 10 is shown another form of connection between the weight 9V and the wire 7. A short section of wire 7W is rotatably connected in the lower end of the weight as indicated in Fig. 1. The other end of this short section is rotatably connected to a steel strap 18 having its ends bent at right angles. The opposite end of this strap is rotatably connected to the wire 7. By this arrangement whatever may happen in the tumbling of the weights the possibility of rotation of the wire relative to the weight is insured.

In Figs. 11 and 12 is shown a modified construction wherein means is provided for turning the weights upon ejection of the bolas from the shell in a manner to insure the rotation of the weights in a predetermined plane with the point of connection of the wire to the rear of the weights. In this embodiment four weights are shown and these weights are of such shape that they can easily be caused to rotate in a plane transverse to the direction of flight and with the point of connection to the wires rearward of the weight as it moves through the air.

Each weight is provided with a projection 19 to which the bolas wire is connected in a manner to permit relative rotation. Preferably, a flat steel strap 20 is rotatably connected to the projection 19 of each weight. The other end of the strap is bent at a right angle and the wire 7 is rotatably connected thereto. In order to insure rotation of the weights in a desired plane, the tops of the weights are restrained from outward movement momentarily when first ejected from the shell to cause a tipping of the lower ends of the weights outwardly. As a convenient restraining means which will not become entangled in the wires, two flat metal strips 21, having hooked ends, engage recesses in the upper outer edges of the weights,

as indicated in the drawings. The weights will be rotating at the rate of rotation of the shell or faster when projected from the shell and by slightly turning the same the continued rotation of the weights at this rate will insure rotation of each weight about an axis parallel to the direction of flight of the shell with the connecting lug 19 to the rear. This results from the spinning or gyroscopic action.

The clamping of the coil between the copper ring 15 at the top of the coil and the base member 16 at the bottom of the coil can be made such as to hold the coil against rotation relative to the shell during gun discharge and the initiation of the shell rotation. If desired, the coil may be more or less secured to the casing by solder or the like to prevent rotation or slip-back and the casing may be rigidly secured in position in the shell. If desired also the shell may be made slightly elliptical in cross-section to inhibit relative rotation of the coil and shell during gun discharge.

The foregoing particular description is illustrative merely and is not intended as defining the limits of the invention.

I claim:

1. A projectile of the character described comprising, in combination, a shell, a bolas comprising a plurality of weights and wires each connected to one of said weights and all twisted together, said wires as so twisted being arranged in a coil within said shell.

2. A projectile of the character described comprising, in combination, a shell, an inner casing in said shell, a bolas within said shell comprising a plurality of weights and wires connecting the weights and an explosive charge positioned to expel the inner casing and bolas from the shell upon explosion, the wires being twisted together in a cable and coiled within the inner casing, the direction of coiling relative to the direction of rifling of the gun with which the projectile is to be used being such that upon projection the coil will rotate toward the point of pull-off and the direction of twist being complementary to the direction of coiling so that the wires will be substantially untwisted during the uncoiling after explosion of the charge.

3. A projectile, as defined in claim 2, wherein the wires are flattened to provide streamlined cross-section.

4. A projectile comprising a bolas consisting of a plurality of weights a wire connected to each weight, the wires being twisted together to form a cable and said cable being formed into a coil, the wires leading from within the coil to the point of connection with the weights whereby the wires are drawn from within the coil when the weights pull them.

5. A projectile comprising a bolas consisting of a plurality of weights and an individual wire connected to each of said weights and the wires being twisted together to form a cable and said cable being formed into a coil, the wires leading from the interior of the coil to the weights and means to rotate the coil in the direction to uncoil the wires toward the weights.

6. A projectile of the character described comprising, in combination, a shell, a bolas comprising a plurality of weights and an individual wire connected to each of said weights, said wires being of streamline cross-section having reduced edges and twisted together with their reduced edges directed inward and as so twisted together being coiled within the shell, the individual wires extending from the coil inwardly and thence to

the weights whereby when the weights separate they draw the wires from the inside of the coil and means to project the bolas from the shell.

7. A projectile of the character described comprising, in combination, a shell, a bolas consisting of several weights and an individual wire connected to each of said weights, the wires being twisted together to form a cable and said cable being formed into a coil, a separable casing within

10 the shell and encircling said coil, the wires leading from within the coil to the point of connection with the weights outside of the casing whereby the wires are drawn from within the coil when the weights pull them.

15 8. A bolas of the character described, comprising, in combination, a plurality of weights, flattened streamlined wires connecting the weights and a central connector to which the wires are connected between the weights and which hold the 20 wires in streamline flight position with one edge forward at said connectors.

25 9. A bolas of the character described, comprising, in combination, a plurality of weights, streamlined wires having a forward rounded edge and a rear relatively sharp edge connecting the weights, a central connector to which the wires are connected between the weights and which hold the 30 wires in streamline flight position with the rounded edge leading at said connectors, and swivel connections between the weights and wires to permit rotation of the weights relative to the wires.

35 10. A projectile of the character described comprising, in combination, a shell, a bolas comprising a plurality of weights and an individual wire connected to each of said weights and twisted together, said wires as so twisted being arranged in a coil within said shell, and means to hold the 40 coil against rotation relative to the shell.

11. A projectile of the character described comprising, in combination, a shell, a bolas comprising a plurality of weights and an individual wire connected to each of said weights, means to eject 45 said bolas from said shell and straps engaging the weights at one end to tilt said weights in a predetermined direction from their position in the shell as ejected.

12. A projectile of the character described comprising, in combination, a shell, a bolas comprising a plurality of weights and an individual wire rotatably connected to each of said weights at one side, means to eject said weights from said shell and straps engaging the weights at one end to tilt said weights as ejected in a predetermined direction from their position in the shell.

13. A projectile comprising a bolas consisting of a plurality of weights and wires connected one to each of said weights, the wires being twisted together to form a cable and said cable being formed into a coil, the wires leading from within the coil to the point of connection with the weights whereby the wires are drawn from within the coil when the weights pull them, together with rotatable connections between said wires and weights including roller bearings whereby rotation of the 60 weights will not twist the wires.

14. A projectile comprising a bolas consisting of a plurality of weights and wires connecting said weights, the wires being twisted together to form a cable and said cable being formed into a coil, the wires leading from within the coil to the point of connection with the weights whereby the wires are drawn from within the coil when the weights pull them, the wires being connected to the weights 70 adjacent one side thereof and extending from the

point of connection in a direction opposite the direction of rotation given to the weights by the rotation of the shell whereby the pull of the wires on the weights will check the rotation thereof.

15. A projectile of the character described comprising a bolas consisting of a plurality of weights each eccentric to the axis of the shell and wires connected to the weight and to each other, said wires being twisted together in a cable, said cable being formed into a coil, the direction of coiling relative to the direction of rifling of the gun, with which the projectile is to be used, being such that upon projection the coil will rotate toward the point of pull-off, and the direction of twist being complementary to the direction of coiling so that the wires will be substantially untwisted during the uncoiling.

16. A projectile of the character described comprising, in combination, a shell, a bolas within said shell comprising a plurality of weights each eccentric to the axis of the shell and wires connecting the weights to each other, and means to expel the bolas from the shell, the wires being twisted together in a cable and coiled within the shell, the direction of coiling relative to the direction of rifling of the gun, with which the projectile is to be used, being such that upon projection the coil will rotate toward the point of pull-off and the direction of twist being complementary to the direction of coiling so that the wires will be substantially untwisted during the uncoiling after expulsion of the bolas from the shell.

17. A projectile comprising a bolas consisting of a plurality of weights and wires connected one

to each of said weights, the wires being twisted together to form a cable and said cable being formed into a coil, the wires leading from within the coil to the point of connection with the weights whereby the wires are drawn from within the coil when the weights pull them, together with rotatable connections between said wires and weights whereby rotation of the weights will not twist the wires.

18. A projectile comprising a bolas including a plurality of weights and wires connected to the weights and to each other, the wires being twisted together to form a cable and said cable being formed into a coil.

19. A projectile adapted to rotate when shot from a rifled gun comprising a bolas consisting of a plurality of weights, each eccentric to the axis of the projectile and individual wires connected to said weights and to each other, the wires being twisted together to form a cable and said cable being formed into a coil wound in a direction such that the rotation imparted by the rifling of the gun tends to unwind the coil toward the weights.

20. A projectile of the character described, comprising, in combination, a shell, a casing of light weight within said shell, a bolas comprising a plurality of wires twisted together and coiled within said casing, weights, one connected to each wire, and an explosive charge positioned to project said bolas and said casing from said shell upon explosion.

HUBERT WELLCOME.
